COMPRESSOR OR THE LIKE

Emile Dupont, Antibes, France

Application July 28, 1939, Serial No. 287,166
In France February 3, 1939

3 Claims. (Cl. 230—131)

An airplane flying at a high altitude, where the air pressure is low, must be supplied with air or carbureted air through the medium of a compressor providing in the engine inlet pipe a pressure comparable to the atmospheric pressure on the ground.

The first object of the present invention is to reduce the power required by the compressor by increasing the efficiency of the latter.

The present invention also tends to decrease the heating of the carbureted air before its inlet into the engine cylinders. Then, it becomes possible to increase the compression ratio without any risk of creating pre-ignition.

The invention also has for its object to reduce the angular speed of the compressor impellers, due to the increased efficiency.

The present invention also tends, further to the reduction of speed of the compressor wheels, to simplify or suppress the speed reduction mechanism interposed between the airplane engine and the compressor, and to reduce the quantity of lubricant used.

The invention will be understood from the following specification.

An impeller unit or turbo-compressor, in accordance with the invention, is represented, by way of example, in the enclosed drawings wherein:

Fig. 1 is a side elevation with one half shown in section of the form of apparatus with two fluid streams arranged in series.

Fig. 2 represents respectively in its left and right halves cross-sections of the upper half of said turbo-compressor, perpendicularly to its axis, along the lines 2¹ 2¹ and 2² 2² of Fig. 1.

Fig. 3 represents, on a large scale, a transverse cross-section through the paddles or blades and the parallelograms of the velocities which characterize the operation of the apparatus.

Fig. 4 is a sectional view of one manner for attaching a paddle or blade.

Fig. 5 is a sectional view of an alternative manner of attaching a blade.

Figs. 6 and 7 are respectively front and sectional views of another way of attaching the paddle, in accordance with the invention.

Fig. 8 is a schematic cross-section of a modified form of turbine in accordance with the invention, but having both streams in parallel.

The form of impeller or turbo-compressor represented in Figs. 1, 2 and 3 is mounted on a drive shaft 1 which may be, for example, the end of an airplane engine shaft. A wheel 2 made of a light alloy or any other metal, is fixed on the drive shaft 1, by means of a key 3 and a conical fitting. Said conical fitting 4 is combined with a washer 5 held by a stop nut 6 screwed on the end of shaft 1 and positively secured.

A disc 7 made of a light alloy, or any other

metal, is attached to wheel 2, for instance, by means of screws 8 distributed around a circumference next to the hub of the shaft 1. The disc 7 contacts wheel 2 on machined bearing surfaces 9 and 10 and further has a circular groove 11, next to the circumference of the attaching screws 8, and in which a corresponding rib 12 of the wheel 2 fits.

The disc 7 and the wheel 2 are further joined by filled lugs 13 having radial ribs, next to the periphery of said wheel 2.

Thus, a concentric attachment of the disc 7 to the wheel 2 and a positive attachment of said disc 7, with respect to said wheel 2 are obtained in the circumferential direction, although leaving to said two elements, the possibility of expanding separately with respect to each other, in radial directions.

The disc 7, hollow in its central part, is closed on its radial end by means of a light iron sheet plate 14, fixed to the edges of said disc 7, by means of screws 15 for example. Said plate 14 is shaped in accordance with a cone, the outline of which corresponds to the shape of the gaseous stream at the inlet of the apparatus. It further serves to shield nut 6 used for the mounting of the wheel 2 on the shaft 1.

The wheel 2 and the disc 7 which constitute the body of rotor 2—7 carry on their outer surface, circular arrays of paddles or blades 16¹ 16² 16³ for the disc, 7 and 17¹ 17² 17³ . . . for the wheel 2, called movable paddles or blades. The outline of said paddles (Fig. 3) 16¹ . . . 17¹ is different for different rings, and according to the characteristics of the apparatus (speed and power).

The paddles 16¹ . . . 17¹ may be made of a light alloy, brass, or another metal. They may be obtained by the transverse cutting of bars rolled to their outline, along the length of said cut elements. Round or polygonal stems 18 are machined, long enough to permit the riveting of the paddles on the wheel 2 or the supporting disc 7 (Fig. 4).

In the case where the paddles have a considerable length, or if the speed of the wheel is high, said paddles 16¹ are further maintained at their end by the riveting of stems 19 on the rings 20 forming hoops (Fig. 5).

The paddles 16—17¹ may also (Figs. 6 and 7) be fitted in the circular grooves 21 of the wheel 2, with interposition of the intermediate parts 22—22² on which the edges of the groove 21 are hammered down as at 23.

In the case of paddles having a small projection, they can be milled on the body of the wheel itself.

In any case, the paddles may be hooped at their end with a riveted ring, as shown in Fig. 5.

On a cylindrical bearing part 23 of the wheel

2 is mounted a plate or cheek 24, made of a light alloy or any other metal, carrying on its internal face radial ribs 25 cast or stamped together with said cheek or fixed by welding or brazing.

The cheek 24 constitutes the principal part of the stator; it is fixed to the frame 50 or to the case of the engine; it may even be an integral part of said case.

On the outer face of said plate or cheek 24 two circular bearing parts 26—27 are machined, on which is fixed an annular discharge collector 28, made, for instance, of light iron plate which is connected to the engine inlet.

Tight connection between the plate or cheek 24 and the cylindrical bearing part 23 of the wheel 2 is obtained by means of a rib joint 29 forming a tight packing.

The longitudinal play of the whole of the shaft 1 and wheel 2, with respect to the plate or cheek 24, must be less than the play between the paddles 16¹ . . . 17¹ and the wall facing them. To this end, the drive shaft 1 must be held longitudinally in the bearing next to wheel 2, so that the expansion of said shaft 1, in the direction perpendicular to the stator, may be as small as possible.

Opposite to the paddles 17¹ 17² . . . of the wheel 2 and fixed to the radial ribs 25 of the plate or cheek 24, a second stator plate or cheek 30, made of a light alloy or another metal, is mounted.

Said second plate or cheek 30 of the stator is fixed to the radial ribs 25, for instance with bolts 31 passing through eyes 32 cast projecting over the ribs 25.

Said second cheek 30 has a slightly conical shape. It carries circular arrays of stationary blades or paddles 31¹ 32² fixed in the same way as the movable paddles 17¹ 17² . . . on the wheel 2 and interleaved between said movable paddles 17¹ 17².

Said stationary paddles 31¹ 31² which are subjected to no stress due to centrifugal force, may be made of a metal of less strength than that used for the movable paddles 16¹ 17¹.

Finally, the rigorously concentric mounting of the cheek 30 on the wheel 2 is obtained by means of the stems 32 carried by each rib 25, and fitting in a circular groove 33 provided in the cheek 30.

The stator is completed with an external housing or cheek 34 made of a light alloy or another metal, forming a housing for the stator, and being fixed at the periphery of the cheek 24, with bolts 35 and concentric fitting 36, for instance.

Said stator housing 34 carries, on its internal face, which is substantially perpendicular to shaft 1, circular arrays of stationary paddles 31¹ 31² . . . interfoliated or mutually interstitially positioned between the rings of movable paddles 16¹ 16² 16³ . . .

The housing 34 is continued by an axial tube 38 which constitutes an axial fluid connection to outside the casing, and with flange 39, for the connection of the impeller or compressor inlet pipe.

The housing 34 and the cheeks 24—30 constitute the body of the compressor stator.

The two stationary paddles, nearest to the periphery 31¹ and 31², are attached by the above described means, such as riveting, to the wings of a tie-ring 40 of U beam section, made of a light alloy or any other metal. The inner cylindrical face of said ring 40 is provided with grooves forming a tight packing, with the cylindrical surface of the wheel 2 and disc 7.

One of the wings of the ring 40 is provided with

a groove 41, in which is tightly fitted a collecting ring 42 formed of two walls 42¹ 42² perpendicular to the axis and of a cylindrical wall 42³ joining the former on the outside. The wall 42² of the ring 42 is joined to the cheek 24 of the stator by a set of tubes 43, welded, screwed or rolled in the wall 42². Furthermore, said tubes 43 pass across the stator plate or cheek 24 and have a threaded part 44 extending beyond a flat bearing surface provided on the outer face of the cheek 24 around the orifice.

A nut 45, screwed on the threaded part 44 and bearing against the flat surface, insures the tightness of the assembly.

Finally, the stator housing 34 may be provided, on its outer surface, with ribs 46 for strengthening same and furthering the cooling of said housing.

The operation of the above described apparatus is the following:

Assuming the rotor revolving in the direction of the arrow f (Fig. 3), consider a ring of movable paddles 17ⁿ near the shaft and the rings of stationary paddles 31ⁿ⁻¹ 31ⁿ located immediately adjacent thereto. The stationary paddles on the stationary inside ring 31ⁿ, (Fig. 3), which are inclined so as to obtain the correct inlet of the fluid incident on the movable paddles on the further out ring 31ⁿ⁻¹, act on the contrary as diffusor for the ring of movable paddles 17ⁿ, and as distributor for the ring of movable paddles 17ⁿ⁻¹.

Each ring 17¹ . . . of movable paddles thus gives an independent compression, the whole of the concentric rings 17¹ 17² . . . creating, in series, all together, successive stages of compression (or of expansion, should the device operate as a motor).

The gaseous fluid thus sucked in by the axial pipe 38 of the housing is progressively compressed by the rings of movable blades 16ⁿ . . . 16³ 16² 16¹ on the disc 7, then passing between the tubes 43, said fluid is brought back towards the axis of rotation, under the action of the pressure, through the passage between the first stator plate or cheek 24 and the second stator plate or cheek 30, said fluid being then radially guided by the ribs 25. The fluid then passes through the opening near the shaft of the second stator cheek 30 and is directed outwardly in a centrifugal direction into the rings of stationary paddles 31¹ and movable paddles 17. Then, the fluid undergoes a second series of successive compressions, caused by the rotation of the rings of movable paddles 17 carried by the wheel 2. The fluid compressed to a maximum escapes into the discharge collector 28, after passing through the tubes 43 which constitute peripheral fluid connections to outside the casing.

Both faces of the rotor, constituted by the wheel 2 and the disc 7, are thus used for obtaining two stages of compression added one to another and permitting to obtain a high final pressure.

Instead of adding, in series, said two stages of compression, obtained on each face of the rotor, said two compressions can be put in parallel so as to double the delivery of the apparatus, the final pressure being that obtained with the paddles of one single face of the rotor. This double stream compressor is schematically represented in Fig. 8.

It essentially comprises a stator composed of an inlet collector 51 near to the axis, of two conical cheeks 52¹ 52² carrying the rings of sta-

tionary paddles 37¹ . . . 37⁴ . . . , and of an outlet collector 53.

The rotor is composed of a wheel 54 fixed on the shaft 55 and presenting, on each one of its faces, rings of movable paddles 16¹ 16² . . . 17¹ 17² . . . mutually interstitially positioned or interfoliated between the rings of stationary paddles 37¹ 37² . . . 37⁴ 37⁵ of the stator.

The two streams are conducted on all sides of the wheel 54 in a symmetrical and centrifugal manner.

The power taken by each one of the ring units of the compressor of the invention is expressed by:

$$W = \frac{p}{g} (U^1 V^1 \cos \alpha^1 - U^0 V^0 \cos \alpha^0)$$

where

p is the weight of fluid treated per second,
 g the acceleration of gravity,
 U^1 the velocity at the periphery of the rotating movable paddle,
 V^1 the absolute velocity of the fluid at the outlet of the movable paddle,
 α^1 the angle made between said first mentioned two velocities,
 U^0 the velocity at the inlet of the rotating movable paddle,
 V^0 the absolute velocity of the fluid at said inlet,
 α^0 the angle made between said last mentioned two velocities.

It is apparent from Fig. 3, that the inclination of the movable paddles, at the inlet, ahead of the movement, results in giving angle α^0 a value greater than 90°, therefore, to give to the term ($U^0 V^0 \cos \alpha^0$) a positive value.

In the same way, the slight inclination of the movable paddles 17ⁿ at the outlet, ahead of the movement, has for consequence to decrease towards zero the value of the angle α^1 . The cosine of said angle α^1 approaches unity and the value of the term $U^1 V^1 \cos \alpha^1$ increases and approaches the value $U^1 V^1$.

The value of the angles α^0 , α^1 may evidently vary although being limited by the paddles machining considerations.

In the same way, the height of the paddles, projected on a radius, may also vary, the height of said paddles and their pitch being however capable of permitting an appropriate guiding of the fluid stream.

Numerical example.—Supposing a rotor having a diameter of 523 m. m., rotating at 2500 R. P. M. and having 6 rings or stages of compression on each one of its faces. The angles α^0 are supposed equal to 135° everywhere. The air delivery is supposed to be 1 kg. per second.

For the respective rings or stages of compression, the work done is:

1st stage	150 kgms. (kilograms-meter-second)
2nd stage	200 kgms. (kilograms-meter-second)
3rd stage	285 kgms. (kilograms-meter-second)
4th stage	390 kgms. (kilograms-meter-second)
5th stage	504 kgms. (kilograms-meter-second)
6th stage	625 kgms. (kilograms-meter-second)

I. e. total 2,154 kgms. for one face

and 4,308 kgms. for both faces.

A wheel of an ordinary compressor, of same outside and inside diameter, provided with radial paddles and rotating at the same speed, would have given, under the same conditions, an internal power of 500 kgms. per face of wheel, i. e. 75

1000 kgms. for both faces, i. e. a power four times smaller.

The efficiency of the compressor of the invention is about 0.90. The internal power of 4308 kgms., above indicated, corresponds, taking said efficiency into account, to an increase in pressure sufficient to restore at the inlet of an engine operating at an altitude of 4000 meters a pressure equal to that prevailing at the ground.

The apparatus of the invention also presents the following technical advantages:

1. The internal efficiency of the apparatus is important, it reaches 0.90 while the known compressors have an efficiency around 0.70. The

15 mechanical efficiency of the apparatus is also high due to the eliminating of gears and the reduction to a minimum of the bearings and surfaces of friction.

The overall efficiency of the apparatus of the 20 invention offers, for said two reasons, great advantages.

2. The heating of the compressed fluid is small for the reasons which cause the increased efficiency. In the case of airplane engines, this advantage permits high compressions with no risk of pre-ignition.

3. The peripheral circumferential speed of the rotor which, in known compressors, reaches 300 to 400 meters per second, is reduced, in the apparatus of the present invention, to about 70 meters for the same result.

4. Said moderate speed permits the direct drive of the rotor by the engine shaft end, which does away with step up gears, reduces the overall dimensions and the losses of energy through friction.

5. Oil drawing is suppressed in the case where the compressor is direct driven by the engine shaft.

40 6. The compressor of the invention further permits, as in the known centrifugal compressors, to increase the total compression ratio by ordinary means, such as the use of several turbine rotors in series, or the increase of the circumferential speed, by increasing the diameter or the speed of the wheel.

The invention extends to the impeller devices described, either serving as turbo-compressors, or, on the contrary, as turbine motor supplied 50 with a compressed fluid.

The invention extends to the devices described, whatever may be the fluid utilized, steam, gas, liquid. The invention is also capable of many applications and, in particular, of the following:

55 1. Steam turbines,
2. Recompression of lost vapors to recover heat,
3. Gas or steam compressors in the refrigeration industry,

60 4. Low and high pressure compressors in the compressed air industry and aviation,
5. Small compressed air turbines in the industry of pneumatic tools and apparatus,

65 6. Internal combustion or other gas turbines,
7. Hydraulic turbines for the production of power by using water falls,

8. Centrifugal pumps for all liquids, at low and high pressures.

I claim:

70 1. In a rotary impeller unit, a substantially flat rotor having on each of its two radial faces a series of concentric mutually spaced ring arrays of rotor impeller blades, a stator comprising a casing surrounding said rotor and having two inner radial faces each provided with a series of

concentric mutually spaced ring arrays of stator impeller blades which are positioned to interstitially occupy the ring spaces between said ring arrays of rotor impeller blades, an axial fluid connection to outside said casing, peripheral fluid connections to outside said casing, said rotor and stator comprising path defining means for defining a fluid path from said axial connection radially outwardly through a first said series of ring arrays on one rotor face, thence radially inwardly through a clear channel inside said casing which extends along the inside of the outer wall thereof, and thence radially outwardly through a second said series of ring arrays on the other rotor face to said peripheral external 15 connection.

2. An impeller unit according to claim 1, said peripheral fluid connections extending substantially parallel to the axis of said rotor from adjacent the periphery of said rotor to outside said stator casing and extending through said clear channel.

3. An impeller unit according to claim 1, said stator having two adjacent substantially radial plates one of which forms a part of the external casing and the other of which constitutes one stator inner radial face carrying a series of ring arrays of stator impeller blades, and said two adjacent stator radial plates forming between them said clear channel.

EMILE DUPONT.
